SPOTTING RACK APPARATUS

John G. Smith, West Memphis, Ark.

Application September 5, 1944, Serial No. 552,739

2 Claims. (Cl. 273—22)

1

This invention relates to a spotting rack apparatus and it is primarily an object of the invention to provide an apparatus of this kind particularly intended to be used in public billiard halls to provide means whereby an effective accounting can be had of the games played.

Another object of the invention is to provide an apparatus of this kind including a spotting rack for proper placement of balls for play upon a playing surface, such as a billiard table, and wherein such spotting rack is held normally under check control in an out-of-the-way or in an inoperative position but readily releasable for spot racking upon deposit of a suitable coin or other check.

The invention consists in the details of construction and in the combination and arrangement of the several parts of my improved spotting rack apparatus whereby certain important advantages are attained, as will be hereinafter more fully set forth.

In order that my invention may be better understood, I will now proceed to describe the same with reference to the accompanying drawings, wherein:

Figure 1 is a view partly in elevation and partly in section illustrating a spotting rack apparatus constructed in accordance with an embodiment of my invention and in inoperative adjustment with respect to the table;

Figure 2 is a view similar to Figure 1 but showing the apparatus lowered with the spotting rack on the table;

Figure 3 is an enlarged fragmentary view taken lengthwise of the apparatus as illustrated in Figure 1, the line of section being on 3—3 of Figure 6;

Figure 4 is a fragmentary sectional view taken substantially on the line 4—4 of Figure 3;

Figure 5 is a view similar to Figure 4 but showing certain of the parts in a second position;

Figure 6 is a sectional view taken substantially on the line 6—6 of Figure 2;

Figure 7 is a sectional view taken substantially on the line 7—7 of Figure 2; and

Figure 8 is a view in top plan of the sliding sleeve or block and associated spotting rack.

As disclosed in the accompanying drawings, T denotes a conventional type of table used in the playing of pocket billiards or pool and kindred games and normally held at a desired height above one end portion of the table T is a conventional spotting rack or triangle S.

Carried by the corner portions of the rack or triangle S are the outstanding eye members 1 to which are affixed the lower extremities of the flexible members 2 which are arranged in upward convergence and have their upper extremities secured to the eye members 3 depend-

2

ing from a sleeve or block 4 snugly but freely surrounding the elongated and vertically disposed housing 5 herein disclosed as rectangular in cross section although such configuration may be otherwise as preferred.

Carried by and disposed over the upper end of the housing 5 is a top plate or head 6 having a central opening 7 in communication with the housing 5 and through which pass the flexible members 8. These members 8 are disposed over the diametrically opposed guide rollers or pulleys 9 mounted upon the plate or head 6 and extend outwardly and exteriorly of the housing 5 and with their exterior extremities secured to the upstanding members 10 carried by the sliding block or sleeve 4 at substantially diametrically opposed parts.

The flexible members 8 extend down within the housing 5 through the opening 7 in the top plate or head 6 and the extremities of the members 8 within the housing 5 are secured, as at 11, to the top of a weighted member W.

Anchored, as at 12, to the top plate or head 6 at diametrically opposed points and preferably to the side faces thereof are the lower extremities of the upstanding hanger straps 14 which extend lengthwise of and have close contact with the associated hanger straps 15 which depend from the ceiling of a roof or other support.

The straps of one of the pairs, as 15, are provided therewith along with the slots 16 through which are directed the shanks of the headed bolts 17 carried by the straps 14. Threading on the bolts 17 are the conventional nuts 18 whereby the straps 14 and 15 may be effectively held in desired selective adjustment lengthwise thereof as may be determined by the desired elevation of the housing 5 above the table T or kindred surface with which the apparatus is to be employed.

The member W is preferably twice the weight of the sliding block or sleeve 4 and the spotting rack S is preferably of a weight substantially three-fourths of the weight of the member W so that the combined weights of the rack S and the block or sleeve 4 is greater than the weight of the member W, whereby before the rack S can be returned to its normally raised or elevated position the rack S must be manually lifted. As the spotting rack S is manually lifted, the weighted member W will drop down within the chamber 5, or stack as it may be called, and thus automatically raise or lift the block or sleeve 4 and the rack S to a height determined by the extent of downward travel of the member W within the housing or stack 5.

As the member W reaches substantially the limit of its downward movement, an end portion of a weighted dog or pawl 19 carried by the weighted member W operatively engages a suitably positioned keeper member 20 carried by the

housing or stack 5 and extending inwardly thereof, whereby the spotting rack S will be retained in its fully raised position at a required distance above the table T to afford no interference to the playing on the table T.

The keeper member 20, as herein disclosed, comprises a sliding blade which is normally maintained extended within the housing or stack 5, under the action of a retractable spring 21. The pawl or dog 19 has one end portion pivotally connected, as at 22, between the arms 23 depending from the weight W. This mounting of the pawl or dog 19 permits the same to readily swing upwardly to allow it to pass the keeper member 20 but has contact with an underlying shoulder 24 to prevent the pawl or dog 19 swinging outwardly and downwardly beyond the horizontal so that when the pawl or dog 19 is extended below the keeper member 20, the weighted member W will be effectively held against upward movement.

In the present embodiment of the invention, the blade 20 is carried by the inner end portion of a slide 25 and disposed horizontally and radially therefrom. The slide 25 operates through a side portion of the housing or stack 5 at the lower extremity thereof and also extends within a boxing B carried by the adjacent portion of the housing or stack 5.

The wall a of the housing or stack 5 separating the housing or stack 5 from the boxing B is provided with a suitably formed opening 26 to permit the desired movement of the slide 25 and blade 20 whereby the blade 20 may readily move within the housing or stack 5 into proper position to be engaged by the dog or pawl 19 or the blade 20 moved outwardly of the stack or housing 5 a distance sufficient to free the blade 23 from the dog or pawl 19 so that the spotting rack S may be readily pulled down manually to desired position upon the table T to spot the balls.

The spring 21 hereinbefore referred to is operatively connected, as at 27, to the outer end portion of the slide 25 and to the front face portion 28 of the forwardly enlarged lower portion of the housing or stack 5. The slide 25 extends within this enlarged portion 28, or receptacle as it may be called, and coacts with a check or coin slide 29 of a conventional type which extends within the portion or receptacle 28 through the outer or front face. Upon the proper placement of a coin or check, the slides 25 and 29 will be caused to have unitary inward movement, whereby the blade 20 will be shifted into the boxing B and free of the extended dog or pawl 19. When a coin or check is not applied, the slide 29 will have endwise movement entirely free of the slide 25.

The coin mechanism is of a conventional type wherein, when the slide 29 has been shoved inwardly a required distance, the coin or check will be allowed to drop within the receptacle 28. It is also to be stated that the coin mechanism in itself forms no particular part of the present invention and may be of such a character as may be preferred.

A wall of the housing or stack 5 carries a conventional type of counting meter 30 including an operating member 31 extending within the chute or stack 5 for engagement by the weighted member W as it moves downwardly, whereby effective record may be had of the number of times the rack S is used. The character of the counting meter forms no part of the present invention although it is to be stated that the operating arm 31 is of a type to be ineffective during the

movement thereof as effected by the upward travel of the weighted member W.

A wall of the housing or stack 5 also carries a normally open switch 32 interposed in an electrical circuit, said switch also including an operating arm 33 for contact by the weighted member W as it passes downwardly to close the circuit. The circuit is adapted to be comprised in an electrically operated cash register or other electrically operated reporting means which may be positioned at a point remote from the apparatus to provide further means whereby may be obtained a recording of the number of times the rack S is lowered.

From the foregoing description it is thought to be obvious that a spotting rack apparatus constructed in accordance with my invention is particularly well adapted for use by reason of the convenience and facility with which it may be assembled and operated.

I claim:

1. A ball racking apparatus, comprising a relatively long hollow housing, means supporting the housing vertically, a head member carried upon the upper end of the housing, a sleeve member encircling the housing and having sliding movement thereon below the head, a spotting rack, means coupling the spotting rack with the sleeve for suspension from the sleeve below the lower end of the housing, a weight member slidably positioned within the housing for free movement therein, rotatable guide members carried upon such head at the upper end of the housing, flexible connectors attached to the weight member and passing upwardly from the housing across said rotatable members and connected with the sleeve, and means within the lower part of the housing for automatically securing the weight member upon its movement downwardly in the housing to a predetermined position, said weight member securing means being operable from outside the housing for the release of the weight.

2. A ball racking apparatus, comprising a relatively long hollow housing, means supporting the housing vertically, a head member carried upon the upper end of the housing, a sleeve member encircling the housing and having sliding movement thereon below the head, a spotting rack, means coupling the spotting rack with the sleeve for suspension from the sleeve below the lower end of the housing, a weight member slidably positioned within the housing for free movement therein, rotatable guide members carried upon such head at the upper end of the housing, flexible connectors attached to the weight member and passing upwardly from the housing across said rotatable members and connected with the sleeve, means for releasably securing the weight member against reverse movement after it has moved downwardly to a predetermined position in the housing, comprising a keeper element supported at the lower end of the housing for sliding movement in a path extending transversely of the housing, means operable from outside the housing for shifting the keeper member, and a vertically swinging latch carried upon the weight and positioned to engage the keeper upon the downward movement of the weight to said predetermined position, to pass to a position beneath the keeper, said latch being constructed and arranged to assume a horizontal position beneath the keeper to hold the weight against upward movement until the keeper is shifted.

JOHN G. SMITH.
